UNITED STATES PATENT OFFICE.

FREDRICK J. SMITH, OF BROOKLYN, ASSIGNOR OF ONE-HALF TO JAMES H. BEALS, JR., OF NEW YORK, N. Y.

APPARATUS FOR STEREOTYPING.

SPECIFICATION forming part of Letters Patent No. 297,023, dated April 15, 1884.

Application filed November 29, 1882. (Model.)

To all whom it may concern:

Be it known that I, FREDRICK J. SMITH, of the city of Brooklyn, in the county of Kings and State of New York, have invented a new 5 and Improved Apparatus for Stereotyping, of which the following is a full, clear, and exact description.

My invention relates to improvements in a stereotyping apparatus; and it consists in the 10 peculiar construction and arrangement of parts, as hereinafter fully described, and pointed out in the claims.

Reference is to be had to the accompanying drawings, forming part of this specification, 15 in which similar letters of reference indicate corresponding parts in all the figures.

Figure 1 is a perspective view of my new and improved stereotype-casting flask placed on an ordinary casting chair or frame, the 20 flask being shown open and arranged for casting type-high six-column plates. Fig. 2 is a sectional elevation of the flask thus arranged, the parts of the flask being closed and clamped together. Fig. 3 is a sectional elevation of the 25 closed flask, arranged for casting type-high single columns. Fig. 4 is a perspective view of the removable foot-pieces used in casting type-high single columns. Fig. 5 is a perspective view of a piece of a six-column type- 30 high stereotype-plate made in accordance with my invention. Fig. 6 is a perspective view of a type-high single-column stereotype-plate, and Fig. 7 is a side view of one of the side bars used in casting six-column thin plates.

35 A represents the cope, and B the nowel, of the flask. These parts are hinged together by the adjustable hinges *a a*, composed of the slotted plates *b b*, formed on the nowel, the eye-plates *c c*, formed on the cope, and the rod *d*, 40 which passes through the plates *b* and *c*. The adjustment of the hinge is accomplished by means of the nuts *e e* on the eyebolts *f f*, that are placed on the rod *d* near its ends, and pass up through the perforated plates *i i*, formed 45 on the upper ends of the slotted plates *b b*. The cope *A* is formed with the edge flanges *g g*, for holding the core-plate *C*, as shown in Figs. 1 and 2, or the core-plate *D*, as shown in Fig. 3, these plates being interchangeable in the 50 cope. The nowel *B* is formed with holes near

its rear or lower end, to receive the pins *h h* of the foot-piece *E*, (shown in Fig. 1,) or the pins *j j* of the foot-piece *F*, (shown in Fig. 4,) and it is slotted at its forward or upper end, as shown at *b' b'*, Fig. 1, for holding the forward or upper ends of the bars *G G*, as shown in Figs. 1, 2, and 3, or for holding the side bars, *H H*. (Shown in Fig. 7.) The rear or lower ends of the bars *G G* and the side bars, *H H*, are held in the notches *f' f'* and *e' e'*, made in the foot-pieces 60 *E* and *F*, as will be understood from the drawings and the following description: The core-plate *C* in this instance is formed with six space-ribs, *l l*, and is used for casting the six-column type-high stereotype-plate *J*, (shown in Fig. 5,) 65 while the core-plate *D* is formed with only five space-ribs, *k k*, and is to be used for casting the single-column type-high plates *K*. (Shown in Fig. 6.)

In casting the ordinary thin stereotype-plates 70 that are subsequently to be mounted upon blocks of wood with this flask, the core-plate *C* will be removed from the cope, side bars, *H*, will be put in the place of the bars *G G*, (shown in Figs. 1 and 2,) the hinges *a a* will be properly adjusted, and the matrix will be placed upon the nowel between the side bars, and the flask closed, and the metal poured in the ordinary way. For casting the type-high six-column plates *J*, the flask will be arranged as 75 shown in Figs. 1 and 2, the spaces between the ribs *l l* of the core *C* serving to form the supporting-ribs *j' j'* along the under side of the plate. In casting the type-high single-column plates *K*, the core-plate *D* will be substituted 80 for the core-plate *C* in the cope, the foot-piece *F* for the foot-piece *E* on the nowel, and the intermediate bars, *G G*, will be put in place, as shown in Fig. 3. These intermediate bars, *G G*, it will be seen, come, when the flask is closed, 85 in the center of the spaces between the ribs *k k* of the core-plate *D*, thus forming spaces on either side of the bars for making the ribs *k' k'* of the columns *K*, as will be understood from Fig. 3. 90

The advantages of the flask are obvious from the above description, and need not be further explained.

Having thus described my invention, I claim as new and desire to secure by Letters Patent— 100

1. In a stereotyping apparatus, the combination, with a nowel having its forward end slotted, of a foot-piece having its forward side notched and removably secured to the rear end 5 of the nowel, and removable side bars engaging with the notches and slots of foot-piece and nowel, substantially as herein shown and described.

2. In a stereotyping apparatus, the combination, with nowel B, provided with holes near its rear end, and the slots b' at its forward end, of the foot-piece E, provided with the pins h and notches e', and the removable side bars G, substantially as herein shown and described.

3. The slotted hinge-plates b b, formed on 15 the nowel B, and having the perforated plates i i, formed at their upper ends, in combination with the eye-plates c c, formed on the cope, the rod d and the eye-bolts f f, placed on the rod and passing up through the plates i i, and nuts 20 e e on said eyebolts, for adjusting the hinge, substantially as set forth.

FREDRICK J. SMITH.
